(57) **CLAIM**

The ornamental design for a connector for a server rack, as shown and described.

DESCRIPTION

FIG. 1 is a front perspective view of the first embodiment showing a new design for a connector for a server rack in accordance with the present invention;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof;

FIG. 7 is a bottom plan view thereof;

FIG. 8 is a rear perspective view thereof;

FIG. 9 is a front perspective view of the second embodiment showing a new design for a connector for a server rack in accordance with the present invention;

FIG. 10 is a front elevation view thereof;

FIG. 11 is a rear elevation view thereof;

FIG. 12 is a right side view thereof;

FIG. 13 is a left side view thereof;

FIG. 14 is a top plan view thereof;

FIG. 15 is a bottom plan view thereof; and,

FIG. 16 is a rear perspective view thereof.

The broken lines shown in the various figures are included to show unclaimed subject matter only and form no part of the claimed design.

1 Claim, 6 Drawing Sheets
